SURVEYING INSTRUMENT

Donald C. Johnson, Berkeley, Calif.

Application September 2, 1942, Serial No. 456,981

1 Claim. (Cl. 33—70)

(Granted under the act of March 3, 1883, as
amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to geometrical instruments and it is more particularly concerned with instruments useful in surveying.

The general object of this invention is the provision of means which will enable a person without the assistance of any other person to make surveys in cases where a high degree of precision is not required, such as in laying out farm terraces, drainage lines, gradients, and so forth.

In the accompanying drawings there is illustrated an embodiment of this invention which is explained in the following description and considered together a full understanding may be had by those skilled in the art.

In the drawings:

Figure 1 is a side elevational view of a preferred embodiment of the principal instrument of this invention.

Figure 2 is a side elevational view of the instrument illustrated in Figure 1.

Figure 3 is a section along the line 3—3 of Figure 2.

Figure 4 is a front elevational view of a form of target rod of the invention.

Referring with more particularity to the drawings in which like numerals designate like parts, the principal instrument is mounted on a rod 11 of non-circular cross-section upon which a sleeve 12 is slidably disposed. The sleeve 12 is provided with a thumb screw clamp 13 for fixing it at different positions along the rod 11. A linear scale 14 is delineated on the rod 11 for indicating different positions of the sleeve 12 thereon. A horizontal spindle 15 is rigidly secured to the sleeve 12 which pivotally carries radial arms 16 and 10 which are integral with a circular arc 17 having delineated thereon an angular scale 18. The arms 16 and 10 are supported between an inner flange 19 and an outer flange 20 of the spindle 15.

A vertical arm 21 is secured to the spindle 15 and terminates on the outer face of the arc 17 adjacent the scale 18 at which point it is provided with a reference mark 22 for indicating relative positions of the arc about the spindle. Another vertical arm 23 also secured to the spindle 15 terminates on the opposite face of the arc 17. A thumb screw 24 engages the arms 21

and 23 above the arc 17 by means of which they can be pressed together to clamp the arc in different positions of rotation.

A telescope 25 is secured to the bottom of the arc 17 by means of arms 26 and 27. This telescope has the usual eyepiece 27A and cross hairs 28 and, as in certain conventional forms of telescopic levels, is provided with an aperture 29 through the top of the casing. Light entering 10 through this aperture is reflected to the eyepiece of the telescope by means of a mirror 30 or other suitable reflector. In conventional forms a spirit level is placed on the casing of the telescope over this aperture so that it can be observed through the eyepiece simultaneously with objects in the principal field of view of the telescope. However, in accordance with this invention a spirit level, designated by the numeral 31 is secured on the flange 20, and the telescope is so disposed that the aperture 29 is radially opposite the center of the bubble tube of the level 31, so that the bubble is not affected by the pivotal movement of the telescope and can be seen through the eyepiece 27A when the telescope is 15 in different angular positions. The aperture 29 is covered with a window 32 of glass or other suitable material.

The bottom of the rod 11 is provided with a foot plate or shoe 33 to support the instrument over the ground and a spike 34 for fixing the rod to the ground. The spike 34 is longitudinally 20 slideable on the lower end of the rod and is held thereon by guide bands 35 and 36 and a spring dowel clamp 37 for which dowel holes 38 are provided through the spike. Screws 39 and 40 are carried by the bands 35 and 36 to tighten the spike in different positions against the rod. An aperture 41 is provided in the shoe 33 through which the spike slides.

The target rod 42, illustrated in Figure 4, is substantially like the ordinary target rods, having a linear scale 43 and an adjustable target 44, except that the bottom is provided with a shoe 45 and spike 46 like that provided for the instrument rod 11. Similar means are also provided for guiding and releasably securing the spike to the rod.

The rod 11 can be set on the ground and supported by forcing the spike 34 downward into the ground and clamping it with the screws 39 and 40 and dowel clamp 37. The rod can be leveled while looking through the telescope in different angular positions, since the level bubble is reflected to the eye of the observer through the aperture 29. The target rod 42 can also be placed

at any point on the ground and held there by means of the spike 46.

A few examples will illustrate ways in which this invention can be used.

In laying out and staking a grade ditch or other grade line, the target rod 42 should be fixed firmly to the ground by means of the spike 46 with the shoe 45 resting on the ground at one end of the line to be staked. The target 44 is adjusted to about the level of the operator's eyes and clamped. With the telescope on the instrument rod 11 set at the same elevation, the operator measures or paces off from the target rod the intervals at which he wishes to set stakes in the approximate direction on the grade desired. He then sets the telescope at an angle corresponding to the grade desired and clamps it in position with the thumb screw 24. With the shoe 33 of the instrument rod resting on the ground at the first interval point and the rod 11 in a plumb position, the operator sights the telescope in the direction of the target 44, the while maintaining the instrument plumb by keeping centered the level bubble which he can see while sighting the telescope. The operator then notes how much the horizontal wire of the telescope misses the target and moves the instrument rod up or down-hill as may be necessary to correct for the error. If greater accuracy is desired, the procedure may be repeated with less approximation. A stake, or other marker, is then driven in the ground at the final position of the instrument rod. The same procedure is repeated for each point at which it is desired to place a stake or marker.

To determine the grade of an existing slope, both the target 44 on the target rod and the instrument on the instrument rod 11 are set at the same vertical height. The target rod is then placed in a plumb position at one end of the slope

line and secured to the ground in the manner previously indicated. The instrument is then taken to the other end of the slope line where the instrument rod is placed in a plumb position.

5 The operator then loosens the thumb screw 24 and pivots the telescope until he centers its horizontal cross hair on the target, the while manipulating the rod to keep it in a vertical position. The telescope is then clamped by means of the thumb screw 24 and the vertical angle or slope is read on the scale 18 opposite the reference mark 22.

10 The above examples demonstrate the manner in which this invention can be used in some primary surveying operations and they are not intended to limit the scope of the invention. The manner of using the invention for other surveying operations will be apparent to those skilled in the art. In some cases it is advantageous to use more than one target rod, as well as one or more of the conventional line rods ordinarily used in surveying. The use of such additional apparatus is within the scope of this invention.

15 Having thus described my invention, I claim:

20 A surveying instrument comprising a rod, a sleeve slidable on and along said rod, means for releasably securing said sleeve to said rod in adjusted position, a spindle fixed to said sleeve normal to said rod, a telescope swingably supported on said spindle with its line of sight normal to said spindle, a spirit level secured to said spindle in a plane parallel to the vertical plane through said line of sight, means projecting an image of said level in the field of view of said telescope in 25 all angular positions of said telescope on said spindle, an angular scale concentric of said spindle and secured to said telescope, and means for clamping said scale and telescope to said spindle.

30 DONALD C. JOHNSON.
